UNITED STATES PATENT OFFICE.

ALLEN O. MILLER, OF SEATTLE, WASHINGTON, ASSIGNOR TO WESTERN BLOWER CO.,
OF SEATTLE, WASHINGTON, A CORPORATION OF WASHINGTON.

BOILER.

Application filed July 3, 1922. Serial No. 572,381.

This invention relates to horizontal steam and hot-water boilers.

The principal object of my invention is the improvement of boilers of this type to render the same more efficient in operation and economical in the consumption of fuel.

More specific objects and advantages of the invention will appear in the following specification.

10 The invention consists in the novel construction, adaptation, and combination of parts hereinafter described and claimed.

In the accompanying drawings,

15 Figure 1 is a view partly in side elevation and partly in longitudinal section of a boiler embodying my improvements. Fig. 2 is a view partly in front elevation and partly in transverse section of the same, the section- 20 alized part of the furnace baffle being taken through 2-2 of Fig. 1. Fig. 3 is a detail sectional view through 3-3 of Fig. 1. Fig. 4 is a perspective view of one of the baffle blocks shown detached.

25 As shown in the drawings, my improved boiler comprises a base member 5, an intermediate wall section 6 supported thereon, and a cylindrical shell 7 which seats in substantially semi-circular recesses 8¹ and 9¹ provided in both the front and rear walls 8 30 and 9 of said wall section and between the side walls 10 and 10¹ of the latter.

35 The walls of said wall section are hollow to provide therein water spaces which communicate with each other. The shell 7 is made to provide therein and adjacent to its rear end, a cavity 11 extending upwardly from its underside to about its midheight to afford a combustion space between a water containing leg 12 at the rear and the back tube sheet 13 for the boiler tubes 14.

40 Said shell is separably connected from in front of and to the rear respectively of the space 11 with the interior of the wall 9 by means of pipes 15 and 16 which include couplings, such as 15¹ and 16¹. The pipe 15 is preferably connected to the lower portion of the wall 9 and is accessible for cleaning out through the medium of a hand hole 17 for which is provided a plate closure 18. The other pipe 16, above mentioned, is located outside of the boiler and is preferably connected with the interior of the wall 9 at an elevation above the connection therewith of the pipe 15.

45 At diametrically opposite sides of the

shell the same is connected with the chambers of the side walls 10 and 10¹ by means of interfitting elbow attachments 19 and 20, of which the attachments 19 are secured to the shell and extend into sockets provided in 60 the attachments 20.

The joints between the complementary attachments are rendered water tight, as shown in Fig. 3, by means of a gasket 21 employed in the socket element below a 65 spigot end of the other attachment 19 and acting in cooperation with a packing surrounding the part 20 and held in place by a gland 42.

70 Located directly below the back tube sheet 13 and extending upwardly from the base member 5 and between the side walls 10 and 10¹ of the intermediate section 6 is a baffle wall 23 of a refractory material and which constitutes the rear wall of the boiler furnace 24. This baffle wall, moreover, is located in front of the pipe coupling 15¹ to 75 protect the same from the region 24¹ of most intense heat within the boiler.

75 Extending downwardly into said furnace 80 from the shell 7 is an arch-wall 25 composed of a plurality of blocks having heat refractory characteristics. As illustrated, said arch consists of upper courses of blocks 26 which are supported upon a lower course of 85 blocks 27 and 28 which, in turn, is supported upon an arch tube secured at its opposite ends in the inner plate elements 30 of the respective side walls 10 and 10¹.

85 More particularly, said arch-tube is 90 formed with bends 31 and 32 to provide substantially vertical and horizontal elements 33 and 34 to allow for the expansion and contraction of the tube due to changes of 95 temperature and also afford connections at different elevations with the respective side walls to promote the passage of water through the tube from one of said walls to the other one.

95 The lower course of arch blocks have 100 interengaging tongue and groove connections, indicated by 35 and 36 and are each provided in its underside with a groove 37 to receive the tube part 34 to avoid confusion, the groove 37 is omitted from Fig. 4.

105 The groove 37 of the end block 28 is continued as at 37¹ up one of its sides to receive therein the portion 33 of the arch tube which serves to prevent the wall tilting in a forwardly or rearwardly direction. The 110

blocks 27 and 28 are furthermore, provided in their meeting sides with complementary channels 38 to provide passages to direct the gases of combustion in a downwardly and rearwardly direction through the arch wall instead of below the latter over the fuel bed. 39 represents a door through which the furnace is supplied with fuel. It is to be noted, with the exception of its intermediate or cavity section, that the shell 7 is cylindrical, which is not only an inexpensive construction possessing strength and rigidity, but ensuring corresponding contractive and expansive characteristics at both ends of the shell and with respect to the end wall connections.

In practice, the furnace is stoked to normally afford a fuel bed of sufficient height to close the opening below the arch-wall 25 whereby the latter divides the furnace chamber 24 to provide a firing compartment in front of the arch wall and a combustion chamber 24¹ to the rear thereof. This combustion chamber communicates through the throat opening above the baffle 23 with the combustion space 11 inside of the boiler body.

In operation, a partial combustion of the fuel gases occurs within the firing space of the furnace and the unconsumed gases and flames escape through the arch passage 38 into the combustion chamber 24¹ and against the hot baffle 23. The combustion is completed in the chamber 24¹ and the cavity 11, whence the hot smoke and gaseous products of combustion travel through the boiler tubes to the chimney connection.

What I claim, is,—

1. A boiler comprising a shell having cylindrical end portions and a cavity in its underside between said cylindrical end portions, a furnace member provided with water-containing side and end walls, said end walls being provided with arcuate concavities in which the respective circular portions

of said shell are seated in front of and to the rear respectively of said shell cavity, communicative connections between the interior of said shell and the upper portions of the water spaces within the side walls of the furnace member and communicative connections between the rear and medial cylindrical portions of the shell and the upper and lower portions, respectively, of the water space within the rear wall of said furnace member.

2. A boiler comprising a shell having cylindrical end portions of the same diameter and a cavity in the underside of the shell between its cylindrical portions, a furnace member having water containing side walls communicatively connected with said shell member, a refractory baffle located directly below the rear wall of the cylindrical front portion of the shell extending upwardly into the furnace chamber of the second named member, and an arch wall extending downwardly from said shell into said chamber at a distance in front of said baffle, said arch wall being provided with passages arranged to cause fuel gases travelling therethrough to be directed rearwardly and downwardly against said baffle.

3. A boiler having a furnace located between water containing side walls, a pipe secured at its extremities to said walls and affording communication between the water spaces thereof, said pipe being formed with a horizontal portion extending substantially across the entire width of the furnace chamber and a substantially vertical portion located adjacent to one of said walls, an apertured arch wall supported by the horizontal portion of said pipe and maintained in vertical position by means of the substantially vertical portion of the pipe.

Signed at Seattle, Washington, this 23 day of May, 1922.

ALLEN O. MILLER.
